UNITED STATES PATENT OFFICE.

EDWARD T. BURROWES, OF PORTLAND, MAINE.

FOLDING TABLE.

1,235,432.

Specification of Letters Patent. Patented July 31, 1917.

Application filed November 26, 1913. Serial No. 803,130.

To all whom it may concern:

Be it known that I, EDWARD T. BURROWES, a citizen of the United States, residing at Portland, in the county of Cumberland and 5 State of Maine, have invented certain new and useful Improvements in Folding Tables, of which the following is a specification.

This invention relates to improvements in folding tables of the kind used for card 10 playing, etc., and it comprises an improved molding for the edges of the table, and improved means for latching the braces for the table legs, whereby the braces may be unlatched to fold the table by exerting pressure 15 against the legs, without the necessity of taking hold of the braces to unlock the same.

In the accompanying drawing,

Figure 1 is a perspective view of a folding table embodying my invention;

Fig. 2 is an inner perspective view of one of the corners of the molding;

Fig. 3 is a top plan view of one of the corners of the molding;

Fig. 4 is a section through the table top on the line 4-4 of Fig. 1;

Fig. 5 is an inner side elevation of a portion of the one-piece molding shown in Fig. 6, the view being taken at the joint in the 30 molding;

Fig. 6 is a plan view of a one-piece molding for the table;

Fig. 7 is a plan view of a corner of a molding with an ornamental corner-piece 35 set therein;

Fig. 8 is a bottom plan view of the table, with the legs folded;

Fig. 9 is a section through a portion of the table top showing one of the legs and 40 its brace extended, the section being taken approximately on the line 9-9 of Fig. 8;

Fig. 10 is a similar view showing the leg and brace folded;

Fig. 11 is a perspective view of one of the 45 braces; and,

Fig. 12 is a detail view illustrating the operation of the brace.

Referring to Figs. 1 to 4, inclusive, of the drawing, A indicates the table as a whole, 50 comprising a top a of fiber, pulp-board, or similar material, a frame b which supports the top at its margins, and to which the top is suitably secured as by means of tacks, a cover c consisting of cloth, leather, or other

suitable material, which, as shown in Fig. 55 4, extends over the top and downwardly on the sides of the frame, a metal molding d which extends around the frame and partly over the top and cover, legs e, hinged to the frame, and braces f for latching the legs in 60 their extended positions. The edges of the table top are rounded, as shown at 1, Fig. 4, and the lower outer edges of the frame are likewise rounded, as shown at 2, although the rounding of the latter edges is not essential. 65 The upper portions of the outer faces of the frame are substantially flush with the margins of the top, as illustrated in Fig. 4. Shoulders 2^a are formed on the side bars of the frame, the depth of these shoulders being substantially equal to the combined 70 thicknesses of the cover and molding, and below said shoulders the side bars are off-set outwardly so that the lower portions 2^b of the side bars are flush with the outer face of 75 the molding in the completed table.

The molding d is made of metal, preferably in sections and joined together as illustrated in Figs. 2 and 3, but it may be in one continuous piece, as illustrated in Fig. 6. 80 As shown in Figs. 2, 3, and 4, the metal bars or strips which constitute the molding are of comparatively thin material, flat on the portions 3 which fit against the sides of the frame, and curved or flanged inwardly in 85 their upper portions as indicated at 4, so as to conform to the curvature of the edges of the table top. The ends of adjacent sections of the molding are beveled, as indicated by the line 4^a, Fig. 3, so that the sections will fit 90 neatly together and, for the purpose of assembling the parts, each section is provided with a tongue 5, which is riveted to the inner side of the adjacent section, as illustrated in Figs. 2 and 3. To make seamless 95 joints, the sections of the molding may be electrically welded together, and the corners may be capped with separate corner pieces, conforming to the shape of the molding, if desired.

The assembled molding may be applied to the table top after the cover is in position by placing the molding over the table and forcing it downwardly until the curved upper portion of the molding rests firmly against 105 the cover and the lower edge of the molding rests against the shoulders 2^a on the frame. The molding is then secured to the frame

by screws 6, inserted through suitable openings in the molding and extending into the frame.

When in position the molding will set 5 firmly against the cover, obscuring its edges, and the frame and table top form a firm backing for the molding which will prevent it from becoming dented or injured with ordinary usage. The molding forms a neat 10 finish to the table, and the inward turning of its upper portion avoids vertical crevices between the molding and the cover, thus preventing dust and dirt from accumulating between the molding and the cover. To renew 15 the cover, the screws 6 may be taken out and the molding forced upwardly to expose the edges of the cover and the latter may be taken off, a new cover applied and the molding returned to its position on the table.

20 Instead of making the molding in separate strips and connecting the strips together, it may be made in one continuous piece, as illustrated in Fig. 6, by cutting out V-shaped sections from the curved portions 25 of the molding, so as to bevel these portions, and bending the straight portions of the molding to form angles between the sides, the beveled edges in the curved portions being afterward united by welding to form 30 flush and continuous joints. After the molding is bent to the proper form, its ends are connected together by a connecting piece 7, as indicated in Fig. 5, which piece is riveted to the flat portions of the two ends of 35 the molding, making a butt strap joint. In Figs. 5 and 6, the meeting ends of the molding are shown centrally of one side of the molding; but the joint may be made at one of the corners, the strap or connecting piece 40 in that event being bent at an angle to hold the two sides together. This continuous piece molding may be applied to the table top in the same way as the molding composed of united sections above described.

45 Metal corner pieces may be applied to either of the forms of molding above described for the purpose of assembling and strengthening the molding at the corners. Where the molding is made in one continuous piece, however, the sides are held strongly together by the vertical portions of the molding which are bent to form the corners, and the over-turned or flanged portions of the molding may be cut away to 50 insert ornamental corner pieces as illustrated at 8 in Fig. 7. Such an ornamental corner piece may be secured to the table by a pin 8² driven into the top and frame, the head of the pin being attached to the corner 55 piece, but concealed. The ornamental corner piece 8 will lie flush with the molding.

The legs 2 of the table are pivotally connected to brackets 9, each bracket being attached to adjacent side bars of the frame.

The bracket need not be described in detail 65 as the same is made the subject of another application copending herewith. These brackets space the legs a suitable distance from the adjacent sides of the frame to permit of the free operation of the braces 7. As shown, each brace consists of a thin metal bar having an off-set portion 10, which is pivotally connected to a side bar of the frame by a wood screw or pivot pin 11, and the body 12 of the bar is straight 75 and provided on one edge, near its free end, with a rounded recess or depression 14 and an inclined surface 13, which meets the wall of the recess at an angle at the point 15. A stud or pin 16, secured to the leg 2, carries a roller 17 adapted to fit within the recess 14 in the brace. A U-shaped metal strap 18 fits around the brace and the roller and is secured to the leg by the stud 16, which passes through perforations in the 85 strap. A stop pin 19 is secured to the frame between the pivotal point 11 of the brace and the pivotal point of the leg, the stop pin being located so that the brace 7 will bear against the stop when the brace and 90 leg are in their extended positions, as shown in Fig. 9, thus limiting the outward movement of the leg. It will be noted that when a table leg is fully extended, as illustrated in Fig. 9, the shoulder 15 on the brace engages the roller substantially on a line 95 passing through the center of the pivot 11 and the center of the roller, and as the leg swings on a different center from that on which the brace swings, the leg cannot be folded inward unless it is given a sharp rap or sufficient pressure is applied to the leg to cause the roller thereon, bearing on the shoulder 15, to force the brace outward slightly, as illustrated in Fig. 12. 105 The brace will yield sufficiently for this purpose, and the roller will snap over the shoulder, unlocking the leg from the brace. The leg may then be folded, as illustrated in Fig. 10, the pivoted strap 18 causing the 110 brace to fold inwardly with the leg. In unfolding the leg, the roller rides on the inner edge of the brace until the brace is against the stop pin 19 and the roller is about at the shoulder 15, and a slight further movement 115 of the leg causes the brace to yield slightly and the roller snaps over the shoulder and into the recess 17, locking the leg. On the same edge of the brace as the socket 14 is shown a depression 21, this depression being 120 for the purpose of affording clearance for the roller 17 when the leg is folded, as shown in Fig. 10, so that the brace may lie parallel with the table leg.

125 It will be observed from the foregoing, that in folding the table it is unnecessary to handle the brace. Usually, in tables of this kind, the brace must be unlocked from the

leg before the latter can be folded. In the table of the present invention this is unnecessary.

What I claim is:

- 5 In a table, a top, a frame flush with the margins thereof and a rectangular metal molding comprising a sheet metal strip flat in its lower portion and curved laterally in its upper portion, the flat portion of the
- 10 strip being bent to form corners between the

sides, and the curved portions being mitered at the corners, and a connecting piece on the inner side of the molding securing the two ends of the molding together.

In testimony whereof I have affixed my 15 signature in presence of two witnesses.

EDWARD T. BURROWES.
